DISPLAY SIGN

Leonard John Huggett, London, England

Application October 28, 1933, Serial No. 695,584
In Great Britain October 29, 1932

4 Claims. (Cl. 40—32)

This invention relates to travelling signs for advertising purposes, for display in shop windows, or in any convenient position, and may be used as a travelling sign to show titles of cinema plays 5 or the like.

I employ a flat continuous travelling band, carrying a series of slotted saddles or the like, into which are inserted letters of the alphabet representing any advertisement desired, small articles, 10 illustrations or the like, the whole of the working parts being enclosed if so desired in a suitable cabinet, with the exception of the top portion of the travelling band, which may be arranged to travel in a horizontal line above the cabinet, or the travel above the cabinet may be semi-circular or angled as desired, by the use of suitable rollers where necessary, arranged in a casing attached to or independent of the cabinet slotted at the top so that the letters or the like upstand 15 without showing the means of their connection to the travelling band.

A series of flanged pulleys to any number may be employed, over which the endless band will travel, so that a very long band may be employed and carry a multiplication of letters or the like, duplicating one or more advertisements, and if desired the advertisement can be shown 20 at more than one point.

30 In the accompanying drawing:—

Figure 1 shows a plan view of one arrangement of a flat endless band running round the flanged pulleys.

Figure 2 shows a front elevation, with front of 35 cabinet removed showing letters attached to band, without casing covering same.

Figure 3 shows a series of pulleys with band shown without letters running around same.

The direction of the travel of the band *b* is 40 shown by the arrows, travelling over the pulleys *a, c, d, e, f, g, h, k, l, m, n, p, q*.

Any motive power may be employed to drive the travelling band.

A motor *U*, is shown in Figure 2 with driving pulley *V*, and a fly wheel *S*, the shaft taking its 5 bearings between the standards *t*.

The letters or the like used for the advertisements will be interchangeable, so that fresh advertisements can be readily made up to replace others in use.

I claim:—

1. A display sign incorporating an endless band, a bank of pulleys consisting of two rows, each row comprising a plurality of pulleys arranged side by side on a single shaft, the band passing backward and forwards from one row to the other in a manner such that it passes over consecutive pulleys of the two rows in the course of its traverse from end to end of the bank, and provision for returning the band from one end to the other of the bank of pulleys, the band being 20 adapted to receive characters such as letters or advertisements arranged to upstand therefrom.

2. A display sign according to claim 1 wherein the means for returning the band from one to the other of the bank of pulleys, consists of a bank 25 of pulleys which the band traverses from end to end in a direction reverse to its direction of traverse through the primary bank.

3. A display sign according to claim 1, having two or more secondary banks of pulleys, so arranged that the band similarly traverses same 30 in the course of its return motion from end to end of the primary bank.

4. A display sign according to claim 1, having additional pulleys in the plane of endmost pulleys of the bank, said pulleys being disposed at a different elevation, and so arranged that the band passes over them to display the characters in the course of its return motion from one end to the other of the said bank.

LEONARD JOHN HUGGETT.
